DOUBLER

Alexander R. Weibel, Aliquippa, Pa., assignor to
 Jones & Laughlin Steel Corporation, Pittsburgh, Pa., a corporation of Pennsylvania

Application August 3, 1933, Serial No. 683,460

19 Claims. (Cl. 153—13)

This invention relates to doublers for doubling metal sheets and packs. It relates particularly to an improved form of doubler which is relatively simple in construction and hence cheap in manufacture and which performs the functions incident to doubling in an improved and highly efficient manner.

My doubler accomplishes the creasing of the sheet or pack and the compressing of the curl end of the creased sheet or pack in an improved manner, insuring proper and uniform creasing and compression of the curl end to the desired degree. I preferably provide a working floor having an opening therein and a creasing blade operable to crease a sheet or pack and force the creased portion through the opening, whereupon the creasing blade is withdrawn and the sheet or pack is compressed at or adjacent the crease, after which the sheet or pack is mechanically ejected from the opening.

My doubler has numerous advantages arising both by reason of simplicity of construction and economy and effectiveness of function, and the advantages can best be brought out by describing the construction and operation of the doubler.

In the accompanying drawings I have shown a present preferred embodiment of the invention in which

Figure 1 is a plan view of a portion of a doubler with portions removed for the sake of clearness;

Figure 2 is a somewhat diagrammatic horizontal cross-sectional view of a portion of the doubler shown in Figure 1, taken along the line II—II of Figure 4, illustrating the centering mechanism;

Figure 3 is a diagrammatic plan view showing the hydraulic connections for the doubler;

Figure 4 is a transverse vertical cross-sectional view taken along the line IV—IV of Figure 1 with portions cut away;

Figure 5 is a longitudinal vertical cross-sectional view through the doubler with portions cut away;

Figure 6 is a diagrammatic cross-sectional view of the end centering mechanism taken along the line VI—VI of Figure 7;

Figure 7 is a diagrammatic longitudinal vertical cross-sectional view through the end centering mechanism taken along the line VII—VII of Figure 6;

Figure 8 is a fragmentary detail elevational view of a portion of the mechanism;

Figure 9 is a fragmentary plan view of a portion of the mechanism;

Figure 10 is a fragmentary vertical cross-sectional view through the portion of the mechanism shown in Figure 9;

Figure 11 is a fragmentary plan view of a modified centering member construction;

Figure 12 is a cross-sectional view through a

valve, taken along the line XII—XII of Figure 13; and

Figure 13 is a cross-sectional view taken along the line XIII—XIII of Figure 12.

For the sake of simplicity the doubler will be described and its operation explained in connection with the doubling of a single oblong metal sheet, although the doubler is specifically intended for doubling pairs or packs of metal sheets and is also useful with obvious modifications for other purposes.

Referring now more particularly to the drawings, the doubler is preferably mounted on a concrete foundation 2 with a portion of the doubler below and a portion above the floor level 15 of the mill or plant in which it is installed. A pit 3 is provided in the mill floor, the top of the concrete foundation 2 being considerably below the floor level, which is indicated at 4 in Figures 4, 5 and 10. Metal floor plates 5 are provided in conjunction with the doubler so that when the same is installed such plates will cover the pit at the floor level except for certain openings used in operation of the doubler as will hereinafter appear.

The operating parts of the doubler are carried by suitable metal structural members designated generally by reference numeral 6, and which will not be described in detail as they may take any desired or well known form, their design and installation being merely a matter of application of engineering knowledge. However, they are shown in the drawings. The opening through which the creased sheet is forced for doubling is designated generally by reference numeral 7. This opening is relatively long and narrow, its length being at least as great as the width of the widest sheet to be doubled on the doubler and its width being at least great enough to receive the creased portion of the thickest sheet or pack to be doubled together with the creasing blade. The opening 7 is bounded at its opposite sides by guide means 8 which are downwardly and inwardly convexly curved as shown in Figure 5 so as to cooperate with the creasing blade to insure proper creasing of the sheet and to guide the same upon downward movement of the creasing blade. As the guides 8 are subjected to rather heavy stresses, particularly in doubling sheets or packs of considerable thickness, they are of strong and heavy construction as shown in Figure 5. The tops of the guides are disposed at the floor level and cooperate with the floor plates 5 so that smooth curves are provided from the floor level inwardly and downwardly of the doubler. The guide means are clearly shown in plan in Figure 2.

In the use of the doubler the first step is to throw the sheet down upon the floor plates 5 with the longitudinal center line of the sheet generally but not necessarily exactly perpendicu-

lar to a vertical plane through the opening 7 and with the transverse center line of the sheet substantially above or near such openings as indicated in Figure 2. The sheet need not be positioned 5 with any great degree of care by the operator throwing it down, it being merely necessary to orient it in a general way as above mentioned. The sheet is then centered so that its longitudinal center line is substantially exactly perpendicular 10 to a vertical plane through the opening 7 and its transverse center line lies substantially in such plane. The centering of the sheet is accomplished by side centering fingers 9 and 10 and end centering fingers 11 and 12. The operating mechanism 15 for the end centering fingers is illustrated in Figures 6 and 7.

Connected with one of the frame members 6 are three generally downwardly angularly projecting posts 13, 14 and 15. Connected with the 20 posts 14 and 15 is a cylinder 16 having fluid connections 17 and 18 and within which operates a piston 19 carrying a piston rod 20. Suitable packing held in place by a packing nut 21 is provided. The post 13 has an opening 22 to receive 25 the left-hand extremity of the piston rod 20, viewing Figures 6 and 7, the same serving as a guide for the piston rod.

Connected with the piston rod 20 so as to form 30 substantially an integral part thereof is a block 23 from which extend lateral pins 24. Journaled over each pin 24 next the block 23 is a link 25, the opposite ends of the respective links 25 being bent 35 toward one another and receiving a pin 26 held in place by cotter pins 27. Also receiving the pin 26 and interposed between the extremities of the two links 25 is an arm 28 keyed to a shaft 29 mounted in bearings 30.

Also carried by and mounted for rotation with 40 the shaft 29 are a pair of arms 31 which extend generally upwardly and toward each other. Pivoted to the upper end of each arm 31 at 31' is a link 32. A pin 33 passes through the opposite ends of the respective links 32 and carries between such links the end centering finger 11. The pin 33 has its ends passing within generally 45 horizontally extending slots 34 formed in members 35 at the floor level and spaced apart so as to provide between them a slot 36a. The finger 11 has a projection 36 which when the finger is 50 toward the left in the position shown in solid lines in Figures 2 and 5 and in chain lines in Figure 7 extends generally downwardly, but which upon movement of the finger toward the right engages a cam track 37 shown in Figures 5 and 7, causing 55 the finger to rotate in the clockwise direction to assume the upright position shown in chain lines in Figure 5 and in dotted lines in Figure 7.

The pins 24 also carry the extremities of the 60 arms 33 of a yoke 39 which is provided with a threaded head stem 40. An adjusting turnbuckle 41 provided with lock nuts 42 cooperates with the stem 40 and a similar stem 43 on a yoke 44 carrying a pin 45 which also carries between the arms of the yoke 44 the upper extremity of an arm 46 65 keyed to a shaft 47 mounted in bearings 48. Also mounted for rotation with the shaft 47 is an arm 49 carrying a yoke 50 having arms 51 each carrying a link 52 pivotally connected thereto at 53. The links 52 carry a pin 54 upon which is carried 70 the end centering finger 12 similarly to the mounting for the cooperating end centering finger 11. The pin 54 has its ends passing within generally 75 horizontally extending slots 34' formed in members 35' at the floor level and spaced apart so as to provide between them a slot 36b. The

finger 12 has a projection 36' which when the finger is toward the right in the position shown in solid lines in Figures 2 and 5 and in chain lines in Figure 7 extends generally downwardly, but which upon movement of the finger toward the left engages a cam track 37' shown in Figures 5 and 7, causing the finger to rotate in the counter-clockwise direction to assume the upright position shown in chain lines in Figure 5 and in dotted lines in Figure 7.

The parts just described are so constructed and arranged that upon admission of fluid to the cylinder 16 through the connection 18 the piston 19 will move generally toward the left, viewing Figure 7, causing, through the mechanism just described, the end centering fingers 11 and 12, which are arranged at substantially equal distances from the center of the doubler, to move toward the center of the doubler simultaneously and to substantially the same extent, such respective fingers upon initiation of their movement being thrown into the upright position, thus enabling them respectively to engage the opposite end edges of the sheet thrown down on the doubler floor by the operator. The fingers 11 and 12 will move toward each other in synchronism until the sheet is firmly engaged by both, this insuring that the transverse center line of the sheet will lie substantially above the opening 7.

The sheet is aligned by the side centering fingers 9 and 10, there being two side centering fingers on each side of the sheet to insure proper alignment. The side edges of the sheet are substantially straight and parallel, whereas the end edges of the sheet may not and probably will not be so.

The operating mechanism for the side centering fingers is illustrated in Figure 4. There is provided a cylinder 55 having fluid connections 56 and 57 at opposite ends thereof for operating 40 a piston within the cylinder 55 and which has a piston rod 58 having an intermediate portion 59 formed as a double rack as shown in Figure 4. The lower extremity of the piston rod 58 is guided in a guide block 60. Mounted in the framework at 45 opposite sides of the rack 59 and extending generally longitudinally of the doubler are shafts 61 and 62, respectively, having keyed thereto pinions 63 and 64, respectively, which pinions mesh with the rack 59. The shaft 61 carries two pinions 65, and the shaft 62 carries two pinions 66. Meshing with each of the two pinions 65 is a rack 67 and meshing with each of the two pinions 66 is a rack 68. Each of the four racks 67 and 68 50 is extended toward the right, viewing Figure 4, 55 as a rod and is suitably mounted for sliding movement in a generally horizontal plane and in a direction substantially at right angles to the longitudinal center line of the doubler. Each of the racks 67 carries one of the side centering fingers 10 and each of the racks 68 carries one of the side centering fingers 9. Slots 69 are provided in the floor plates for the side centering fingers 9 and 10 which extend upwardly therethrough at all times. There is no need for providing for disappearance of the side centering fingers as in the case of the end centering fingers because the sheets are thrown down onto the floor and withdrawn generally longitudinally of the doubler so that the side centering fingers are 65 not in the way as the end centering fingers may be under these circumstances.

In Figure 11 is shown a modified form of centering finger. Such finger comprises a bolt 70 extending upwardly from a block 70' carried by 75

5 a rod 11 which may, for example, correspond to any of the rods connected with the racks 67 and 68, the bolt 70 carrying a rotatable hollow cylinder 72 which may conveniently be in the form of a pile of washers, such cylinder being maintained in place by a cotter pin 73. This form has the added advantage that the portion of the centering finger engaging an edge of a sheet is rotatable against such edge whereby to assist 10 in lining up the sheet in the doubler.

Upon admission of fluid to the cylinder 55 through the connection 56 the piston in such cylinder moves downwardly, which also causes downward movement of the piston rod 58 and 15 rack 59. This through the connections above described causes simultaneous equal inward movement of all four of the side centering fingers 9 and 10. Inasmuch as there are two of such fingers at each side of the sheet, the sheet is 20 properly aligned in the doubler as well as being centered in the longitudinal direction by the end centering fingers 11 and 12 above described.

A hydraulic operating system is used, and in order that the operation of the centering mechanism may be understood we shall now refer to Figure 3 in which the hydraulic connections are shown diagrammatically. The fluid which I prefer to use is oil, although other fluids may be utilized. The fluid is pumped under pressure to the 30 pressure line 74. A return line 75 is provided for returning the fluid to the pump through a cooling device in the usual manner. A line 76 runs from the pressure line 74 and is connected with the cylinder 16 at 17 and with the cylinder 35 55 at 57. As this is a direct connection from the pressure line to the respective cylinders the ends of the respective pistons toward the ends of the cylinders at which the respective connections 17 and 57 enter are at all times subjected to the line 40 pressure. However, due to the fact that the piston rods are connected to the respective pistons at the ends nearest the respective connections 17 and 57, the effective areas of the pistons subjected to the line pressure through the connections 17 and 57 are materially less than the effective areas of the pistons presented in the opposite direction. Therefore, when the opposite ends of the pistons are not subjected to line pressure the piston 19 will normally be urged toward 50 the right-hand end of the cylinder 16, viewing Figure 7, and the piston within the cylinder 55 will normally be urged toward the top of such cylinder, viewing Figure 4.

There is provided a valve 77 from which is a 55 connection 78 to the pressure line and a connection 79 to the return line. Said valve also has a third connection 80 which joins the cylinder 16 at 18 and the cylinder 55 at 56. The valve 77 has a stem 81 (Figures 3 and 10), which stem is 60 pivoted by a yoke 82 and a pin 83 to a lever 84 loosely pivoted to the framework at 85 and the opposite extremity of which is loosely pivoted at 86 to a slide 87 carrying a treadle 88 (Figures 2, 9 and 10). The treadle 88, and consequently the 65 valve stem 81, is normally urged upwardly by a coil spring 89 acting between the treadle and a stop 90.

After the operator has thrown the sheet down on the floor of the doubler within the range of the 70 side and end centering fingers, he steps on the treadle 88, pushing the same down against the action of the spring 89 and depressing the valve stem 81. This moves the valve 77, which may be a slide valve of well known construction, so 75 that communication is established from the pres-

sure line 74 through the connection 78, the valve 77 and the connection 80 to the connection 18 to the cylinder 16 and the connection 56 to the cylinder 55. As the relatively large piston areas are disposed in the directions of these respective 5 connections the piston 19 will be moved toward the left, viewing Figure 7, and the cylinder 55 will be moved downwardly, viewing Figure 4. This will cause simultaneous operation of the side and end centering fingers as above explained, 10 and the sheet will be centered on the doubler floor ready for bending. Of course, if a pack of sheets is to be doubled, the pack will not only be centered but the various sheets comprising the pack will be matched with respect to one another. 15 Therefore, the centering mechanism is also sometimes referred to as matching mechanism, although it only performs a matching function when a plurality of sheets are to be doubled at the same time. 20

Upon release of the treadle 88 the valve stem 81 moves upwardly under the action of the spring 89, thus breaking the connection between the pressure line and the pipe 80 and establishing a connection from the pipe 80 to the return line 75 25 through the valve 77 and the connection 79. This relieves the pressure at the right-hand end of the cylinder 16, viewing Figure 7, and the top of the cylinder 55, viewing Figure 4, whereupon the piston 19 moves toward the right to the position shown in Figure 7 and the piston in the cylinder 55 moves upwardly to the top of its stroke. Under these circumstances the centering fingers are withdrawn, the end centering fingers 11 and 12 resuming their inoperative positions as shown in chain lines in Figure 7, and the side centering fingers 9 and 10 resuming their outer or inoperative positions as shown in solid lines in Figure 2. 30

There is provided an upstanding frame 91 40 (Figures 4 and 5) in which is mounted for vertical sliding movement a frame 92 carrying a creasing blade 93. The frame 92 is connected by a key 94 with a piston rod 95 of a piston 96 operating in a vertically positioned cylinder 97 mounted on 45 a cross frame 98 carried by the upstanding frame 91. By reason of the provision of the piston rod 95 the effective area of the piston 96 at its top is substantially greater than the effective area thereof at its bottom. 50

The cylinder 97 is maintained in position between blocks 99 and 100 by bolts 101. Through the respective blocks 99 and 100 are fluid passageways 102 and 103 connecting, respectively, with the inside of the cylinder below and above 55 the piston.

A pipe 104 leads from the connection 102 to the pressure line 74 as shown in Figure 3 so that the bottom of the piston 96 is always subjected to line pressure. A valve 105 which may be similar to the valve 77 is provided and has connections respectively to the pressure line at 106, the return line at 107 and the cylinder 97 at 103. The valve has a stem 108 (Figures 3 and 10) connected with a treadle 109 in a manner precisely 60 similar to the connection between the valve stem 81 and the treadle 88. 65

Normally when the treadle 109 is up, the under side only of the piston 96 is subjected to line pressure and the creasing blade 93 is in its uppermost position as shown in Figure 4. The creasing blade is in such position during centering of the sheet, and while the treadle 88 is still held in depressed position the treadle 109 is also 70 depressed, admitting fluid from the pressure line 75

74 through the connection 106, the valve 105 and the connection 103 to the upper part of the cylinder 96 and causing the piston, and consequently the creasing blade, to move downwardly. The 5 creasing blade engages the sheet which is still maintained in position by the centering fingers and creases the center portion of it downwardly, forcing the same through the opening 7 between the curved guides 8. The piston 96 and creasing 10 blade 93 are shown in their lowermost position in Figure 5, the creased sheet being shown in such figure at 110. The sheet is gradually and uniformly forced down between the guides 8, which action will cause it to pull above the centering fingers, and when this occurs the treadle 28 is released, allowing the centering fingers to resume their outer or inoperative positions. The forcing of the sheet through the opening 7 between the guides 8 tends to some extent to squeeze 15 the opposite portions of the sheet together, and leaves the sheet frictionally held between the guides so that the creasing blade may be withdrawn upwardly while the sheet remains in place as shown at 113 in Figure 5. Upward withdrawal 20 of the creasing blade is effected simply by releasing the treadle 109 which breaks the connection between the pressure line 74 and the upper portion of the cylinder 97, permitting the fluid to pass into the return line through the connection 107. This permits the piston 96 and creasing 25 blade 93 to resume their upper position as shown in Figure 4 due to the fluid pressure through the connections 104 and 102.

There is provided a cylinder 111 in which operates in a substantially horizontal direction a piston 112. Connected with the piston 112 is a piston rod 113 to which is connected through a coupling 114 a ram 115 having a nose 116 carrying a hardened plate 117. The mechanism just described is so positioned that the ram plate 117 normally lies immediately adjacent the crease formed in the sheet by the creasing blade after the creasing blade has been withdrawn upwardly. A back plate 118 similar to the ram plate 117 is stationarily mounted opposite the ram plate as shown in Figure 5.

There is provided a four-way valve 119 having thereto a connection 120 from the pressure line and a connection 121 to the return line. From 50 the valve 119 there are also a connection 122 to the left-hand end of the cylinder 111 as shown in Figures 3 and 5 and a connection 123 to the right-hand end of the cylinder 111. The valve 119 has a valve stem 124 (Figures 3 and 10) which 55 is connected by mechanism similar to the other connecting mechanism above described to a treadle 125 (Figures 2 and 9). When the treadle 125 is in its uppermost position the connections through the valve 119 are from the pressure line 74 through the connection 120, the valve 119 and the connection 123 to the right-hand end of the cylinder 111 and from the connection 122 at the left-hand end of the cylinder through the valve 119, the connection 121 and the return line 75. 60 This insures that the piston 112 and its associated mechanism will be at the left-hand end of their stroke as shown in Figure 5.

Upon depression of the treadle 125 the connections through the valve 119 are changed so 70 that the pressure transmitted from the line 74 passes through the connection 120, the valve 119 and the connection 122 to the left-hand end of the cylinder 111. At the same time the connection from the right-hand end of the cylinder at 75 123 is brought into communication through the

valve 119 with the connection 121 and the return line 75. This causes movement of the piston 112 and ram 115 toward the right, viewing Figure 5, to compress the creased portion of the sheet against the back plate 118, thereby completing the doubling. Upon release of the treadle 125 the fluid connections just described are reversed and the piston 112 and ram 115 move toward the left to their inoperative position as shown in Figure 5. 10

Connected with the coupling 114 at 126 is an arm 127 (Figures 5 and 8) with which is adjustably connected at 128 a rod 129 which is slidably in a direction parallel to the axis of the cylinder 111 and in synchronism with the piston 112. The rod 129 is guided for slidable movement by a sleeve guide 130. 15

Pivoted to the rod 129 at 131 is a latch 132 adapted for pivotal movement in a generally vertical plane. The latch 132 has a recess 133 adapted to cooperate with a block 134 carried by a slide 135 slidably mounted on a pin 136 in such manner that when the latch 132 is engaged with the block 134 as in the solid line position in Figure 8, movement of the piston 112 will cause corresponding movement of the slide 135. The latch 132 is normally resiliently urged downwardly by a compression spring 132' operating between a stationary abutment 133' and a washer 134' carried on a bolt 135' connected with a downward extension 20 136' on the latch. 25

Connected with the slide 135 at 137 is the stem 138 of a valve 139. The valve 139 has a connection 140 to the pressure line 74, a second connection 141 to the return line 75 and a third connection 142 to the lower portion of a cylinder 143 (Figure 5). When the slide 135 is in the right-hand position, viewing Figure 5, the valve 139 is in such a position that the connection 142 to the lower portion of the cylinder 143 and the connection 141 to the return line 75 are in communication so that the piston 144 is in its lowermost position, viewing Figure 5, being urged to such position by gravity. However, upon movement of the piston 112 to the left, viewing Figure 5, and with the latch 132 in engagement with the block 134, the slide 135 is moved to the left and the valve 139 shifted so that direct communication is established between the connection 140 from the pressure line through the valve to the connection 142 to the lower portion of the cylinder 143 which raises the piston 144. 30 40 45

Journaled in the frame at 145 is a shaft 146 on which is mounted for rotation therewith an arm 147. Also connected with the shaft 146 for 50 rotation therewith is an arm 148 carrying at its outer extremity a roller 149 adapted at all times to rest upon the top of the piston 144. Thus, upward and downward movement of the piston 144 controls the angular position of the shaft 146 55 and consequently the position of the arm 147. 60

The arm 147 engages at 150 an ejector 151 which is slidably in a generally vertical plane and has ejecting portions 152, as shown in Figure 2, which upon upward movement of the ejector push out 65 the doubled sheet so that it will fall upon the floor of the doubler or be available for further manipulation.

Upward movement of the piston 144 causes rotation of the arm 147 in the clockwise direction, 70 viewing Figure 5, about the axis of the shaft 146, so as to move the ejector 151 upwardly; and as the upward movement of the piston 144 is caused by movement of the slide 135 toward the left, viewing Figure 5, which latter movement is de- 75

pendent upon movement of the piston 142 toward the left, it will be seen that after the ram has compressed the crease and moves toward the left, viewing Figure 5, to its inoperative position, 5 the ejector then works automatically, without the necessity of any further manipulation or manual control, to eject the doubled sheet.

Also connected with the shaft 146 for rotation therewith is an arm 153 which, upon movement 10 of the arm 147 in the counter-clockwise direction, referring now to Figure 8 instead of to Figure 5, engages a stud 154 carried by the latch 132, thereby causing rotation of the latch 132 in the clockwise direction, viewing Figure 8, about the 15 axis of the pivot 131 and against the action of the spring 132' and releasing the latch from engagement with the block 134, thus permitting the slide 135 to move toward the left, viewing Figure 8, under action of a spring (not shown) which 20 may conveniently be positioned within the casing of the valve 139. The parts are so constructed and arranged that just as the ejector reaches the top of its stroke the latch 132 becomes disengaged from the block 134 by the mechanism just 25 described, so that the piston 144 may return to its lowermost position, this being assisted by the weight of the ejecting mechanism.

A safety device is provided to prevent movement 30 of the ram 115 toward the right, viewing Figure 5, in a compressing movement while the ejector 151 is in its upper or ejecting position. This would likely result in damaging the ejector so as to render the same inoperative. There is provided a shaft 155 journaled in the framework at 156 35 and upon which is mounted for rotation therewith in a generally vertical plane a bell crank lever having a generally vertical arm 157 and a generally horizontal arm 158. The right-hand extremity of the arm 158 underlies the left-hand 40 extremity of the arm 147 as clearly shown in Figure 5. A coil spring 159 connected with the arm 157 near its upper end tends normally to urge rotation of the bell crank lever and associated mechanism in the counter-clockwise direction, viewing Figure 5. The weight of the arm 147 on the arm 158 is sufficient to hold the bell 45 crank lever and associated mechanism in the solid line position thereof against the action of the spring 159, as shown in Figure 5.

When the arm 147 and consequently the ejector 50 151 are in their upper position, the arm 157 underlies the treadle 125 (see Figure 2) to prevent depression of such treadle until the ejector and arm 147 have again moved downwardly to their 55 full line position, as shown in Figure 5. Upon such downward movement the bell crank lever is operated as above explained, turning the shaft 155 in the clockwise direction, viewing Figure 5, and moving the arm 157 to the full line position 60 of Figure 5 so as to clear the treadle 125 and permit depression thereof. By reason of the provision of this safety mechanism, if the operator should inadvertently attempt to depress the treadle 125 while the ejector is in its upper or 65 ejecting position the treadle will be held up by the arm 157 and will not function until after return of the ejecting mechanism to its lower or inoperative position and so that the ejector is clear of the ram.

The various control valves for the hydraulic 70 system are designated purely diagrammatically in the assembly drawings, and these valves may be of any desired or well known construction. Purely by way of example there is shown in Figures 12 and 13 one form of valve which may be 75

used either exactly as shown or by removal of the plug for any of the valves in the hydraulic system.

The valve shown in Figures 12 and 13 is what is known as a four-way valve having four separate fluid connections 161, 162, 163 and 164. 5 The valve proper, which is of the type known as a spool valve, is designated 165. The connection 163 is shown as being closed by a plug 166. Therefore, with the plug 166 in place the valve has only three operative fluid connections 161, 162 and 164. 10

As will be clear upon inspection of Figures 12 and 13, when the valve 165 is in its upper position as shown and with the plug 166 in place the connection 161 is dead-ended and communication is 15 established between the connections 162 and 164. On the other hand, when the valve is in its lower position communication is established between the connection 161 and the connection 162, the connection 164 being dead-ended. This is a well 20 known type of valve and detailed description of it is unnecessary.

The valve of Figures 12 and 13 exactly as shown and with the plug 166 in place is suitable for use as any of the valves 77, 105 and 139 (Figure 3). 25 Assuming, for example, that the valve of Figures 12 and 13 is to be used as the valve 77, the connection 161 would correspond with the connection 78, the connection 162 would correspond with the connection 89, and the connection 164 would 30 correspond with the connection 79.

By removal of the plug 166 the valve of Figures 12 and 13 can be used as the valve 119, in which case the connection 161 would correspond with the connection 126, the connection 162 would correspond with the connection 122, the connection 163 would correspond with the connection 123 and the connection 164 would correspond with the connection 121. With the plug 166 removed and with the valve 165 in its upper position, as 40 shown in Figures 12 and 13, the connection 161 would be in communication with the connection 163. Likewise, with the valve in its lowermost position the connection 164 would be in communication with the connection 163. 45

One particular operating advantage of my doubler is that the sheets are doubled accurately at their transverse center line, there being no tendency thereof to skew or for the crease to be made toward one end or the other of the sheet. 50 This is a desideratum of importance in doubling and one which has been particularly troublesome in the past. Another advantage arises by reason of the use of the ram to compress the creased portion of the sheet immediately following creasing and in a direction substantially at right angles to the direction of creasing. Furthermore, the hydraulic control system has particular advantages in the operation of the centering or matching fingers, the creasing blade, the compressing 55 ram and the ejector. The ejecting operation is rendered entirely automatic and requires no manual control whatever.

While I have shown and described a present 60 preferred embodiment of the invention, it is to be 65 distinctly understood that the same is not limited thereto but may be otherwise variously embodied within the scope of the following claims.

I claim:

1. A doubler comprising sheet supporting means 70 having a doubling passage therethrough, means for creasing a sheet and forcing the creased portion through said passage to double the same, means constructed and arranged to compress the doubled sheet at or adjacent the crease while 75

- a portion of such sheet remains in the doubling passage, and a separately operable control for said last mentioned means.
2. A doubler comprising sheet supporting means having a doubling passage therethrough, a single unitary creasing blade for creasing a sheet and forcing the creased portion through said passage to double the same, a ram operable to compress the doubled sheet at or adjacent the crease, and piston and cylinder means for operating said ram.
3. A doubler comprising sheet supporting means having a doubling passage therethrough, means for creasing a sheet and forcing the creased portion through said passage to double the same, means for withdrawing the creasing means, a ram constructed and arranged to compress the doubled sheet at or adjacent the crease while a portion of such sheet remains in the doubling passage, and separately operable controls for said ram and creasing means.
4. A doubler comprising sheet supporting means having a doubling passage therethrough, means for creasing a sheet and forcing the creased portion through said passage to double the same, means for compressing the doubled sheet at or adjacent the crease, and means for delivering the doubled and compressed sheet, said last mentioned means including a lever and means connected therewith for engaging the sheet.
5. A doubler comprising sheet supporting means having a doubling passage therethrough, means for creasing a sheet and forcing the creased portion through said passage to double the same, means for compressing the doubled sheet at or adjacent the crease while a portion of such sheet remains in the doubling passage, and means for ejecting the doubled and compressed sheet from the doubling passage, said last mentioned means comprising a sheet engaging member reciprocable only substantially in the plane of the doubled sheet.
6. A doubler comprising sheet supporting means having a doubling passage therethrough, means for creasing a sheet and forcing the creased portion through said passage to double the same, means for compressing the doubled sheet at or adjacent the crease while a portion of such sheet remains in the doubling passage, and means cooperating with the crease to eject the doubled and compressed sheet from the doubling passage in the direction opposite the direction of doubling, said last mentioned means comprising a lever and a reciprocable member cooperating therewith for engaging the doubled sheet.
7. A doubler comprising sheet supporting means having a doubling passage therethrough, means for creasing a sheet and forcing the creased portion through said passage to double the same, means for withdrawing the creasing means, means for compressing the doubled sheet at or adjacent the crease, and hydraulically operable means for delivering the doubled and compressed sheet.
8. A doubler comprising sheet supporting means having a doubling passage therethrough, a single unitary creasing blade for creasing a sheet and forcing the creased portion through said passage to double the same, and hydraulically operable means for compressing the same at or adjacent the crease.
9. A doubler comprising sheet supporting means having a doubling passage therethrough, means for creasing a sheet and forcing the creased portion through said passage to double the same, means for compressing the same at or adjacent
- the crease, and separately operable control means for said creasing means and said compressing means.
10. A doubler comprising sheet supporting means having a doubling passage therethrough, means for creasing a sheet and forcing the creased portion through said passage to double the same, means for compressing the same at or adjacent the crease, and separately operable control means for said creasing means and said compressing means, said creasing means and said compressing means being hydraulically operable.
11. A doubler comprising sheet supporting means having a doubling passage therethrough, means for creasing a sheet and forcing the creased portion through said passage to double the same, means for compressing the doubled sheet at or adjacent the crease, means for delivering the doubled and compressed sheet, and separately operable control means for said creasing means and said compressing means.
12. A doubler comprising sheet supporting means having a doubling passage therethrough, means for creasing a sheet and forcing the creased portion through said passage to double the same, means for compressing the doubled sheet at or adjacent the crease, means for delivering the doubled and compressed sheet, and separately operable control means for said creasing means and said compressing means, said creasing means, said compressing means and said delivery means being hydraulically operable.
13. A doubler comprising creasing means, compressing means and ejecting means separate from the compressing means, the ejecting means being operable by the compressing means.
14. A doubler comprising creasing means, compressing means, ejecting means and safety means preventing operation of the compressing means when the ejecting means are in ejecting position.
15. A doubler comprising creasing means, compressing means, separate manual control means for said creasing means and compressing means, and hydraulic operating means for said creasing means and compressing means, said manual control means controlling said hydraulic operating means.
16. A doubler comprising compressing means, control means therefor, ejecting means, and means for rendering said control means inoperative to operate said compressing means while said ejecting means are in ejecting position.
17. A doubler comprising compressing means, control means therefor, and ejecting means separate from the compressing means, said ejecting means being operable by said compressing means to eject a sheet after compressing thereof.
18. A doubler comprising creasing means, compressing means, ejecting means and stop means, said stop means positively preventing operation of the compressing means when the ejecting means are in ejecting position.
19. A doubler comprising sheet supporting means having a doubling passage therethrough, a unitary rigidly mounted creasing blade for creasing a sheet and forcing the creased portion through said passage to double the sheet, piston and cylinder means in alignment and directly connected with said creasing blade for operating the same, and means for compressing the sheet at or adjacent the crease.
